UNITED STATES PATENT OFFICE.

JOHN S. YERGASON, OF NEW YORK, N. Y.

DESIGN FOR A TEXTILE FABRIC.

No. 38,744.

Specification for Design.

Patented Aug. 6, 1907.

Application filed June 24, 1904. Serial No. 214,056. Term of patent 3½ years.

To all whom it may concern:

Be it known that I, JOHN S. YERGASON, a citizen of the United States, and a resident of New York, in the county of Kings and State of New York, have invented a new, original, and ornamental Design for Textile Fabrics, as shown.

The figure is a plan view of the textile fabric showing my design.

I claim:

The ornamental design for a textile fabric as shown.

JOHN S. YERGASON.
